CLAIM

The ornamental design for a cylinder mounting device for electronic scanner used in photographic reproduction, as shown.

DESCRIPTION

FIG. 1 is a perspective view of a cylinder mounting device for electronic scanner used in photographic reproduction showing my new design;

FIG. 2 is an end elevational view thereof;

FIG. 3 is an opposite end elevational view thereof;

FIG. 4 is a top plan view thereof;

FIG. 5 is a front elevational view thereof;

FIG. 6 is a bottom plan view thereof; and

FIG. 7 is a rear elevational view thereof.
